UNITED STATES PATENT OFFICE.

LYNDE BRADLEY AND HARRY L. BRADLEY, OF MILWAUKEE, WISCONSIN.

SHORT-CIRCUITING AND RETRIEVENG APPARATUS FOR RHEOSTATS.

1,148,656.

Specification of Letters Patent. Patented Aug. 3, 1915.

Application filed July 18, 1913. Serial No. 779,694.

To all whom it may concern:

Be it known that we, LYNDE BRADLEY and HARRY L. BRADLEY, citizens of the United States, residing at Milwaukee, county of Milwaukee, and State of Wisconsin, have invented new and useful Improvements in Short-Circuiting and Retrieving Apparatus for Rheostats, of which the following is a specification.

10 Our invention relates to improvements in short circuiting and retrieving apparatus for rheostats, with particular reference to that class of rheostats in which compressible resistance columns are employed, the resistance being varied by varying the pressure.

15 In connection with the use of automatic motor starters, a demand for a starter has developed in which the rheostat will protect the motor at all times and under all conditions when used in combination with reversing switches, dynamic braking systems and special control systems using the so-called operator switch or master switch.

20 The object of our invention is to provide such a starter which will be quick acting, which will make the necessary resistance changes more rapidly than it is possible for the operator to move the reversing switch, or any lever by which the operator may 25 change the working circuits of the motor, whereby the above mentioned demand may be fully satisfied.

25 It will be understood that if a motor starter is connected with a reversible motor, it is desirable and perhaps essential that when the reversing switch is thrown into the reverse position with the motor running at full speed, the starter shall immediately insert resistance in the power circuit to keep 30 the flow of current within safe limits while the motor is being brought to a stop, after which the resistance interposed by the starter should be gradually removed so that the motor may be brought up to the required speed in the reverse direction. Our 35 invention contemplates the provision of automatic means for accomplishing these results in connection with a starter having a compression rheostat, by removing the pressure from the resistance column or columns as soon as the required speed of the motor is attained, said columns having been first cut out from the circuit of the motor or at least removed from the main 40 circuit of the motor by shunting the columns from such circuit. This is accomplished in

our improved apparatus by means of a magnetic switch, and it is therefore only necessary to open this switch in order to insert the required resistance into the circuit, since 60 the pressure has been previously removed from the columns, thereby restoring their resistance to maximum. The time required for opening the magnetic switch is so short that the resistance may invariably be 65 inserted into the power circuit before any change of motor connections can be completed by the operator, no matter how careless he may be.

70 The drawing is a diagrammatic illustration of our invention associated in controlling relation to an electric motor. The various switch board elements are of types well known in common use to those familiar with this art, and they are therefore illustrated conventionally.

75 Compressible resistance columns 1 are preferably composed of graphite disks similar to those described in our former patent for a resistance device, Number 1,054,902, 80 dated March 4th, 1913. The resistance of these columns decreases under pressure. In our improved construction, pressure is applied to the columns by transmitting motion from the plunger 2 of solenoid 3, through 85 bell crank 4 and an equalizing plate or bar 5, having universal joint connection at 6 with one arm of the bell crank and arranged to bear upon movable electrodes 7 which 90 pass into the tubes and bear respectively against the ends of the graphite columns. An electrode 14 is connected with the lower end of plunger 2 by a push rod 16, and as the plunger 2 completes its downward movement, this electrode 14 makes contact with 95 electrode 15, connecting up the winding of magnetic switch 17 in circuit as hereinafter described. When magnetic switch 17 is energized, its plunger 18 moves upwardly until its cross bar 19 connects contact points 100 20. This short circuits the tubes 1. Plunger 18 is provided with a rod 21, adapted, when the plunger is lifted, to actuate a resilient switch bar 22 which controls the circuit of the solenoid 3 at contacts 23. The 105 upward movement of the plunger 18, therefore, not only short circuits the columns 1, but also disconnects the energizing circuit of solenoid 3, allowing spring 25 to retract bell crank 4, raise solenoid core 2 to normal deenergized position, and relieve the 110 pressure upon the columns 1.

The elements above described are connected up with the motor circuit and operate as follows:—It will be observed that the winding of rheostat solenoid 3 is connected 5 through contacts 30 and bar 31 of accelerating relay 32 with blade 33 of the reversing switch 34 and through clip 35 to the — side of the line. Electrodes 7 and 15 are connected through the winding of accelerating 10 relay 32 with switch blade 33 of the reversing switch. Upon closing the line switch 36, the path of the armature current of the motor can be followed from the positive side of the line through series motor field 37, 15 circuit breaker 38, switch blade 39, pivot clip 40, the armature 41, resistance tubes 1, winding of accelerating relay 32, switch blade 33 and circuit breaker 43, to the — side of the line. In the construction shown, the 20 motor illustrated is a compound motor having both shunt and series fields. This is not essential to our invention, as the device will work equally well with a simple shunt or series motor. The current for the shunt 25 field passes from the + side of the line, through series field 37, circuit breaker 38, clips 45 and 46, shunt field 47, and clip 48 to clip 35, circuit breaker 43 to the — side of the line. The circuit of rheostat solenoid 30 3 is from switch blade 39, through clips 50 and 51, contact electrodes 23, switch bar 22, the winding of solenoid 3, contacts 30, and connecting bar 31 of the accelerating relay to — switch blade 33. Upon closing the line 35 switch 36, plunger 2 of solenoid 3 will be drawn downwardly and its motion transmitted through the bell crank 4 to compress the resistance columns 1. This gradually reduces their resistance with consequent in- 40 crease of current in the armature circuit until a point is reached at which accelerating relay 32 lifts the connecting bar or disk 31 and opens the circuit of solenoid 3, causing a momentary cessation of pressure increase 45 upon columns 1 with a tendency to decrease the pressure already attained. The motor, however, continues to accelerate and its in- 50 creasing counter electro-motive force, together with any diminution of pressure upon the columns, reduces the current until relay 32 again closes, whereupon rheostat solenoid 3 again acts to produce further pressure upon the columns 1. This alter- 55 nate action of the solenoid and accelerating relay will be rapidly repeated until solenoid plunger 2 is drawn down sufficiently to bring electrode 14 into contact with electrode 15, thus closing the circuit through the winding 60 of magnetic switch 17, the current now flowing from the lower contact 23 through the winding of switch 17, through contacts 14 and 15, to the — side of the line through accelerating relay 32. But as soon as mag- 65 netic switch 17 is energized, its plunger 18 draws upwardly until bar 21 engages and

lifts switch bar 22, thus deenergizing the solenoid 3. The tubes 1 and relay 32 have in the meantime been short circuited by the upward movement of bar 19 to connect electrodes 20, thereby allowing current to flow 70 from the + side of the line between the armature 41 and columns 1 directly to the — side of the line represented by switch blade 33. It is not essential that the accelerating relay 32 be shunted from the circuit, but this is 75 preferably done, and with — electrode 20 connected below the relay winding, it is obvious that said relay will be short circuited. When the rheostat solenoid 3 is deenergized by breaking its circuit at contacts 23, this 80 would also deenergize magnetic switch 17 but for the fact that when the plunger 18 of the magnetic switch is lifted, contacts 14 and 15 are bridged from the winding of magnetic switch 17 through bar or plate 19 85 and — contact 20.

The rheostat solenoid 3 is comparatively large and possesses considerable magnetic and mechanical inertia. By removing it from the main circuit and permitting it to 90 deenergize as soon as the required motor speed has been attained, we secure the advantages of economy in current, avoid injurious and unnecessary heating of the solenoid and give it an ample retrieving interval, thus insuring restoration of the resistance units to a condition of minimum compression and maximum resistance before any change in the running conditions of the motor will be required. It is therefore evi- 95 dent that whenever the reversing switch 34 is operated, the smaller and quick acting magnetic switch 17 will be deenergized the moment that switch blade 33 lifts from contact 35, thus permitting switch 22 to close 100 contacts 23, whereupon any movement of switch 34 which either brings blade 39 to contact 48 or blade 39 to contact 45 will again close the circuit through rheostat solenoid 3, and the cycle of motor starting. 105 operations above described will again be performed.

A companion application bearing even date herewith, filed July 18, 1913, Serial No. 779,695, shows and describes some of the features illustrated in this application with claims for an alternative structure designed to accomplish the same general purpose sought to be accomplished in the apparatus herein described. In the companion application, however, the construction is such that the shunting of the resistance columns and rheostat solenoid is dependent on the condition of the current passing through the resistance columns, whereas in this application, it is dependent upon the attainment of a predetermined degree of pressure upon such columns.

We claim—

1. The combination with a compressible 110

5 rheostat, of a compressing lever, an electro-magnetic device having a movable member mechanically connected with said lever, and additional electromagnetic means for cutting out said device when said lever has moved a pre-determined distance.

2. The combination with a main electric circuit, of a compressible resistance member, means for establishing said circuit through 10 such member, electro-magnetic means for compressing said member, electro-magnetic means for prolonging the period of increasing compression, and separate electro-magnetic means for deenergizing the compressing means when maximum pressure is attained.

3. The combination with a main circuit, of a compressible resistance member, means for compressing the same, and electro-magnetic means for relieving said member of pressure and removing it from the main circuit during the final operation of the compressing means.

4. The combination with a main circuit, 25 of a compressible resistance member, means for compressing the same, and electro-magnetic means for relieving said member of pressure and removing it from the main circuit during the final operation of the compressing means, said electro-magnetic means comprising a solenoid, a shunt switch for the main circuit adapted to be operated by the solenoid when energized, and means for utilizing the compressing means to close a circuit through the winding of said solenoid, said solenoid being also adapted to maintain its energizing circuit independently of the compressing means.

5. The combination with a main circuit,

of a compressible resistance medium, a rheostat solenoid adapted to compress said medium, a shunt switch, a switch controlling the delivery of current through the rheostat solenoid, and a magnetic switch operating member provided with a movable device adapted to actuate both of said switches to break the circuit through the rheostat solenoid and establish a shunt cutting out the resistance medium from the main circuit, together with a relay adapted to delay the operation of the rheostat solenoid and connected in the portion of the circuit controlled by the magnetic switch.

6. The combination with a main circuit, of a compressible resistance member, means 55 for compressing the same and separate electro-magnetic means for automatically removing it from the main circuit after a predetermined compressing movement has taken place.

7. In an electric current controller, the combination with a main circuit, of a resistance medium, means for producing pressure on said medium, and means for removing said medium from said circuit at a predetermined stage in the operation of the pressure producing means, and means for automatically relieving said resistance medium from pressure after it has been removed from said circuit.

In testimony whereof we affix our signatures in the presence of two witnesses.
